UNITED STATES PATENT OFFICE.

JAMES G. MACLAREN, OF MAMARONECK, NEW YORK.

GOVERNING MEANS FOR PNEUMATIC SYSTEMS.

Application filed October 2, 1918. Serial No. 256,509.

To all whom it may concern:

Be it known that I, JAMES G. MACLAREN, a citizen of the United States, and a resident of Mamaroneck, county of Westchester, 5 and State of New York, have invented an Improvement in Governing Means for Pneumatic Systems, of which the following description, in connection with the accompanying drawings, is a specification, like 10 characters on the drawings representing like parts.

This invention relates to pneumatic dispatch systems and in particular to means for governing an electrically operated or 15 electrically controlled mechanism in conjunction with the movement of the carriers in such a system.

My invention is adapted for the government of various mechanisms which it might 20 be desired to operate in conjunction with such a system. For purposes of illustration I have shown an installation wherein the mechanism governed is an electric motor driving an exhauster which provides suitable 25 sub-atmospheric pressure in the transit tubes to move the carriers therethrough.

My invention will best be understood by reference to the following description of the 30 illustrative embodiment thereof shown in the accompanying drawings wherein:

Figure 1 is a general and partly diagrammatic view of the installation and constitutes a wiring diagram;

Fig. 2 is a central vertical section through 35 a casing forming part of the air conduit and showing the main controlling mechanism;

Figs. 3 and 4 are sections on the lines 3—3 and 4—4 respectively of Fig. 1.

Referring to Fig. 1 of the drawings, I have 40 thereto shown my invention as applied to a pneumatic system operated by sub-atmospheric pressure or vacuum and have shown a double tube vacuum line comprising a dispatch tube 7 leading from the main terminal station at the left hand side of the figure to the branch station at the upper right hand side, and a return tube 9. Operating pressure is provided in these tubes by means of an exhauster 11 driven by an electric motor 13 which draws air through the tubes 45 through the connecting conduit 15 which includes as a part thereof a casing 17 herein-after to be referred to. In the present embodiment of my invention the driving ac-

tion of the electric motor 13 is governed in 55 correlation with the movement of carriers in the tubes 7 and 9.

Any suitable means may be provided for starting the motor when a carrier is introduced into one of the tubes. I have here shown push buttons 19 and 21 at the intake ends of the tubes adapted to be operated when a carrier is placed therein. The manner in which these push buttons start the motor into action will be more fully described hereinafter. In the form here illustrated the mechanism which more particularly involves the novel principles of my invention is adapted to deenergize the motor 13 when the carrier has left or is 65 about to leave the transit tube.

For this purpose I make use of responsive mechanism governed by the speed of the air drawn through the system. It will be understood that if the carrier tubes are 75 empty and the motor is in motion, air will be drawn from the tubes at a definite speed. It will also be clear that, except under particular circumstances hereinafter to be more fully referred to, the presence of a carrier 80 will obstruct the tubes and retard the speed of the air. I make use of this fact in controlling the driving motor 13 or other desired mechanism correlative to the passage of carriers.

Referring more particularly to Fig. 2, I have there shown one suitable form of air speed responsive mechanism housed in the casing 17 already referred to which forms part of the air conduit of the system. As shown in that figure, I may provide a motor in the form of a fan 23 mounted on a spindle 25 revolving in suitable bearings 27 and 29 one of which is in a spider within the casing and 95 the other in the wall thereof, as shown. As will be readily understood, the spindle 25 will be revolved by the fan at a speed dependent upon the speed with which air passes through the casing 17.

Mounted on the spindle 25 exteriorly of the casing is a collar 31, and adapted to slide on the end of the spindle is a sleeve 33 carrying a similar collar 35 connected to the first by flat springs 37 to which are attached weights 39, the whole forming a centrifugal governor of well known type. As the spindle 25 rotates, the weights 39 will

tend to fly outwardly, bending the springs and drawing the movable collar 35 up towards the fixed collar 31. The parts may be so designed that this movement may be utilized, when the fan reaches a certain critical speed, to operate a controlling element which in turn may be used to deenergize the motor 13 or to operate any other desired mechanism.

10 Referring to Fig. 2, I have there shown the speed responsive device operating an electric switch, which mechanism may be housed in a box or case 40 attached to the side of the casing 17. In the figure I have shown a switch lever 41 mounted on rock shaft 43 and carrying the contact maker 45 electrically connected by the flexible conductor 47 to binding post 49 and adapted to be swung clockwise by the spring 51 to engage contact 53. Attached to the rock shaft 43 is a lever 55 normally depressed by the collar 35 to the position shown in Fig. 2 and in that position holding the contact maker 45 away from contact 53 against the force of spring 51. As the speed of air in the conduit rises, rotating the fan 23, the centrifugally moving weights 39 will lift the collar 35 upwardly and permit the spring 51 to swing switch lever 41 and bring contact maker 45 against contact 53. This action may be used to energize any desired circuit such as the one herein shown by way of illustration and which I shall now more fully describe.

15 30 35 Before proceeding to a detailed description of the electrical installation shown in the illustrative embodiment of my invention, I shall, to facilitate the understanding thereof, first describe some of the specific mechanisms here illustrated. These mechanisms appear herein as mounted on a suitable panel board 57, shown at the lower right hand portion of Fig. 1.

The circuit of the driving motor 13 may be opened and closed by means of a suitable electrically operated switch (left hand side of panel board), the switch lever 59 herein forming the armature of a magnet 61. The construction of this switch will best be understood from Fig. 3. When the magnet 61 is energized, attracting the armature, the spring-pressed plunger 63 will engage contact 65 and connect the same through the armature with binding post 67 through the copper strips 69. The switch lever or armature 59 is herein also provided with a downwardly extending arm 71 which carries (see Fig. 1) a bridge rod 73 which when the armature is attracted connects the spring contact leaves 75 and 77. In the present form of the invention the current is supplied to the motor 13 while the switch 59 is closed and therefore there is here provided a holding circuit therefor which might aptly be called a controlling circuit since the continued action of the motor is dependent thereon. This holding circuit may include a circuit closer in the form of a pivoted bridge 79 (see the upper right hand corner of the board 57) which normally connects contacts 81 and 83. Herein this circuit closer is lifted to break the circuit and I may provide for this purpose a solenoid 85 (see Fig. 4) the core of which is adapted at the upper limit of its travel to engage and lift the bridge 79. The solenoid is herein provided with suitable timing or retarding mechanism in the form of a dash pot 87 which causes the solenoid to lift the bridge 79 only at a definitely fixed time after its energization.

20 25 30 35 40 45 50 55 60 65 70 75 80 85 90 95 100 105 110 115 120 125 130

I shall next describe the circuits by which the motor 13 is governed in connection with the dispatch of carriers through the tubes 7 and 9 by means of the installation here shown, disregarding the many variations that might be made therein within the scope of my invention and reserving for the claims the broader statement of the essential principles underlying the same. Referring to Fig. 1, we may assume that a carrier is introduced in tube 7 at the lower end thereof. Suitable controlling means are provided for starting the motor, herein exemplified by the push button 19. When the operator introduces the carrier he will depress button 19 thereby completing the following energizing circuit:—Positive line 89 at the upper part of the board 57, wire 91, post 67, wire 93, coil of magnet 61, wires 95 and 96, push button 19, wire 97, negative line 99. The magnet 61, being energized, attracts armature 59, rocking it counterclockwise viewing Fig. 3 and bringing plunger 63 against contact 65. This completes the circuit for motor 13 as follows:—Positive line 89, wire 91, post 67, armature 59, contact 65, wire 101, motor 13 and wire 103 to the negative line 99. As the push button 19 is only momentarily depressed, a suitable holding circuit for the magnet 61 is provided to continue the energization of the motor. This holding circuit, which might aptly be called the controlling circuit since it controls the energization of the motor, is as follows:—Positive line 89, wire 91, post 67, wire 93, magnet coil 61, wire 95, wire 105 (which may include a suitable resistance as shown), leaf contact 75, bridge 73, leaf contact 77, wire 107, contact 81, bridge 79, contact 83 and wire 109 to the negative line 99. This circuit will remain energized and continue the current in the motor circuit while bridge 79 remains in the position shown in the figures.

20 25 30 35 40 45 50 55 60 65 70 75 80 85 90 95 100 105 110 115 120 125 130

Herein the speed controlled mechanism shown in Fig. 2 is utilized to control the solenoid 85 which in turn lifts bridge 79 and breaks the holding circuit. We may suppose that the carrier has passed through the tube which is no longer obstructed. The

speed of air in the tube then rises, the fan 23 revolves faster, and the centrifugal mechanism acts to release switch lever 41 to the spring, thereby connecting 49 and 53 shown at the left hand side of Fig. 1. This action completes an energizing circuit for the solenoid 85 as follows:—Positive line 89, wire 111, coil of solenoid 85, wire 113, binding post 49 (pass to Fig. 2), flexible conductor 47, contact maker 49, contact 53 (pass again to Fig. 1), wires 115 and 97 to negative line 99. The solenoid is energized, the core rises and after a suitable period of time determined by the action of the dash pot 87 lifts the bridge 79 and breaks the holding circuit already referred to. The magnet coil 61 is deenergized, the switch lever 59 which forms the armature thereof is released, the circuit to the motor is broken and the motor 20 stops.

The utilization of a timed mechanism such as the solenoid 85 and its cooperating dash pot 87 insures discharge of the carrier and also takes care of the special condition 25 before referred to. It may happen that in the carrier tube there is a sharply descending portion in which the carrier under gravity will descend so swiftly as not to obstruct the movement of the air in the tube. Thus, the 30 fan 23 may then speed up and the contact maker 45 close its circuit before the carrier is discharged. The action of the motor will not, however, be interrupted until a measured time after the circuit is closed at 49, 53. 35 Therefore, after the carrier has passed the sharply downwardly tending portion of the tube, the speed of the air in the tube will again decrease, the circuit will be opened again at 49, 53 and the solenoid 85 deenergized before its core has acted to lift bridge 40 79. The core will then drop and the parts be in their initial position ready to operate as described when the carrier is discharged from the tube.

45 In many instances in this specification reference is made to the closing of a circuit, to the energization of a mechanism and the like. It has been done for clearness and definiteness of description. Obviously, in various instances the same effect might be produced by the opening of a circuit or the deenergization of the mechanism by changes within the skill of an electrician without departing from the spirit of my invention.

55 Having thus described the particular mechanism and the particular wiring thereof herein shown for the purpose of illustrating a specific embodiment of my invention, the principles exemplified thereby which I 60 consider new and desire to secure by Letters Patent I shall express in the following claims:—

1. In pneumatic dispatch apparatus, a transit tube, means for producing a flow of air through the transit tube to propel a car-

rier therethrough, a conduit between said means and said tube, means for initiating a carrier-propelling flow of air, and means in the conduit for automatically stopping the carrier-propelling flow of air when a carrier has completed its travel through the tube, said means including a device responsive to the rush of air following the discharge of a carrier from the tube.

2. In pneumatic dispatch apparatus, a central station, an outgoing transit tube leading from the central station and terminating at a distant station, an incoming transit tube having a connection at the distant station with the outgoing tube through which air may flow from one tube to the other, means at the central station having a conduit connection with one of said transit tubes to produce a carrier-propelling flow of air through said transit tubes, means for initiating a carrier-propelling flow of air, and means for automatically stopping the carrier-propelling flow of air when a carrier has completed its travel through either transit tube, said means including a movable vane mounted in said conduit connection and operable by the rush of air following the discharge of a carrier from the tube.

3. A pneumatic dispatch tube apparatus comprising transit tubes through which carriers are moved by an air current, an electrical mechanism associated therewith, an electrically energized device for breaking the controlling circuit of said mechanism, means for definitely retarding the operation 100 of said device after the energizing thereof and means for energizing the same comprising a device responsive to the velocity changes of the air in a tube due to the transit of a carrier and a circuit closer moved by 105 said responsive device and providing for the energization aforesaid.

4. The method of operating mechanisms which are associated with pneumatic dispatch tube systems in correlation with the transit 110 of a carrier through a tube characterized by initiating the operation of a retarded controlling device consequentially on a change in velocity of the air in the system due to the transit of a carrier.

5. In pneumatic dispatch apparatus, a central station, a distant station, a transit tube connecting said stations, means at the central station having a conduit connection with said transit tube for producing 120 a carrier-propelling flow of air through said tube, means for initiating a carrier-propelling flow of air, and means for stopping the carrier-propelling flow of air when a carrier has completed its travel through the tube, 125 said stopping means including a control device external to the conduit connection and a vane mounted in the conduit connection and operable by the rush of air following the discharge of a carrier from the tube. 130

6. In pneumatic dispatch apparatus, a central station, a distant station, a transit tube connecting said stations, means at the central station having a conduit connection 5 with said transit tube for producing a carrier-propelling flow of air through said tube, means for initiating a carrier-propelling flow of air, and means for stopping the carrier-propelling flow of air when a carrier 10 has completed its travel through the tube, said stopping means including a control device external to the conduit connection and a member mounted to extend through a wall of the conduit connection, 15 that portion of the member extending into the conduit connection being provided with a vane operable by the rush of air following the discharge of a carrier from the tube and that portion of the member extending out-

side the conduit connection serving to operate the control device. 20

7. In a pneumatic dispatch apparatus, a central station, a distant station, a transit tube connecting said stations, means at the central station having a conduit connection 25 with said transit tube for producing a carrier-propelling flow of air through said tube, means for initiating a carrier-propelling flow of air, and means for stopping the carrier-propelling flow of air when a carrier has completed its travel through the tube, said 30 stopping means including a rotatable vane mounted in the conduit connection and operable by the rush of air following the discharge of a carrier from the tube. 35

In testimony whereof, I have signed my name to this specification.

JAMES G. MACLAREN.
